UNITED STATES PATENT OFFICE.

ADDIS E. ALBERTIE, OF DETROIT, MICHIGAN.

COLLAPSIBLE CHAIR AND THE LIKE.

1,344,431.

Specification of Letters Patent. Patented June 22, 1920.

Application filed June 18, 1919. Serial No. 305,131.

To all whom it may concern:

Be it known that I, ADDIS E. ALBERTIE, a citizen of the United States, residing at Detroit, in the county of Wayne and State 5 of Michigan, have invented certain new and useful Improvements in Collapsible Chairs and the like, of which the following is a specification.

My invention relates to improvements in 10 collapsible chairs, tables, and similar furniture, and has for its object the provision of a portable, collapsible piece of furniture that can be quickly and easily set up, and readily folded into a compact parcel.

15 A further object is to provide a collapsible chair or the like of great strength though of little weight, and one which will be efficient and durable in use and inexpensive to manufacture.

20 With the above and other objects in view, which will readily appear as the invention is better understood, my invention consists in the novel construction, combination and arrangement of parts to be hereinafter more 25 fully described and particularly pointed out in the appended claims.

Reference is to be had to the accompanying drawings illustrating preferred embodiments of my invention and wherein similar 30 reference numerals designate similar parts throughout the several views.

In the drawings:—

Figure 1 is a side elevation of a collapsible chair constructed in accordance with my invention and in position for use;

Fig. 2 is a side elevation of the foldable supporting member in closed position;

Fig. 3 is a detail plan view of the upper end of one of the seat supports;

40 Figs. 4 and 5 are plan views of details to be hereinafter described;

Fig. 6 is a side view of the upper end of the seat supports with a seat rod secured therein;

45 Fig. 7 is a perspective view of a slightly changed modification of the chair in open position;

Fig. 8 is a detail view of the hinge connecting the parts forming the seat and back;

50 Fig. 9 is a detail side elevation of another form of the supporting member in open position;

Fig. 10 is a similar view with the parts in closed position; and

Fig. 11 is a detail view of the back support. 55

Referring to the drawings, the numeral 5 designates the supporting member for the detachable seat or table portion of the piece of furniture, and comprises legs 6, preferably four in number, to the upper ends of which are pivoted the seat supporting arms 7 adapted to be connected with the corners of the seat or table portion 8. Both the legs 6 and seat supporting arms 7 are preferably 60 constructed of channel section to give lightness and strength, and each arm 7 when folded fits over the leg 6 to which it is pivoted, as shown in Fig. 2. The free ends of the supporting arms 7 are slotted, as at 9, 65 to receive lugs or bolts 10 carried by the side rods 11 of the seat or table portion 8 (see Fig. 6).

The pins or bolts 12 which connect the legs 6 to the arms 7 pass through openings 75 in the frame 13 fixed on the upper end of a hollow central post 14, to the lower end of which are pivoted locking rods 15 adapted when the chair is in use to prevent spreading of the legs under the weight of the person seated thereon. These rods in the modification shown in Figs. 1 to 6 are provided with hooks 16 at their free ends arranged to engage pins 17 extending across the channel section of the legs 6 intermediate their ends 80 (see Fig. 1), and in the modification shown in Figs. 7 to 10 are formed of jointed sections 18 and 19 pivoted to each other and to the legs 6 and central post 14 respectively. 85

Extending through the central post 14 is 90 a normally vertical bolt 20 carrying at its upper end a locking plate 21 provided with grooves 22 arranged to fit over the supporting arms 7 when in open position. In the embodiment illustrated in Figs. 1 to 8 the 95 weight of the bolt and nuts serves to hold the plate in engagement with the supporting arms, while in the modification illustrated in Figs. 9 and 10 a spring 23 is utilized to assist in holding the locking plate down. 100

The seat or table portion of the piece of furniture is preferably made of canvas or other fabric, provided with side rods to strengthen the edges, which carry the means for securing the seat or table portion to the 105 supporting member 5. In the illustrated embodiment these side rods 11 are provided with headed lugs or bolts 10 adapted to fit

into the slots 9 on the free ends of the supporting arms 7 when the chair or table is in position for use. These slots are preferably of the type illustrated in Fig. 3, and 5 permit the ready detachment of the lugs and seat portion from the supporting arms 7 when desired. Pivoted to the side rods 11 are the side rods 25 of a back portion 8^a, also of canvas or similar fabric, and to maintain 10 the back in proper position when the chair is in use I preferably provide a limiting cord or chain 24, the ends of which are connected to the seat and back portions respectively. The upper edge of the back portion 8^a is reinforced by a rod 26, pivoted at one end to one of the side rods 25, while its opposite end is adapted to fit into an eye 27 formed in the other side rod. The canvas portion carries snap-fasteners 28 to secure 15 the flap 29 of the back 8^a in position over the upper rod 26. When the device is to be used as a table the back portion 8^a can be folded down on top of the seat portion 8, or, by detaching one of the retaining cords 20 24, can be opened into parallel position with the seat portion and supported at its free end by an additional prop or supporting member.

The operation of my improved collapsible furniture is believed to be apparent from the foregoing description. When in folded position, as shown in Fig. 2, the legs 6 fit within the channels of the supporting arms 7 and set in alinement with the central post 14. The seat and back portion is detached from the supporting member and can be rolled around the folded supporting member 5, the upper rod 26 of the back portion being swung into alinement with the side rods 25 before rolling. To set up, the seat and back portion in unrolled from the supporting member, the arms 7 are swung upwardly into the position shown in Fig. 1 40 and the hooks of the locking rods 15 are brought into engagement with the cross pins 17 in the legs 6, and the grooves 22 of the locking plate 21 are fitted over the arms 7 in their raised position. The lugs 10 of the rods 11 of the seat portion are then inserted 45 into the slots 9, the back portion 8^a is swung upwardly, and the upper rod 26 is swung into position within the flap 29. The chair is then in position for use.

In the modification shown in Figs. 9 and 50 10 the locking rods are always connected with the legs 6 and the central post 14 so that it is unnecessary to swing the hooks into engagement with the pins on the legs. This simplifies the operation of setting up 60 the chair. Also the spring 23 assists in holding the locking plate 21 in engagement with the arms 7 in their raised position.

While it will be apparent that the illustrated embodiments of my invention herein 65 shown are well-calculated to adequately ful-

fil the objects and advantages primarily stated, it is to be understood that the invention is susceptible to variation, modification and change within the scope of the subjoined claims.

70

Having described my invention, I claim:

1. A collapsible chair or the like having a detachable seat portion and a supporting member therefor provided with legs of channel section, seat supporting arms of channel section pivoted to the legs and adapted to fit thereover when in folded position, a hollow post, means for pivoting the legs therein, locking rods connected to the legs and to said post, a bolt mounted in said hollow post, and a locking plate carried by said bolt and adapted to engage the seat supporting arms when the chair is in position for use.

2. A collapsible chair or the like having a detachable seat portion and a supporting member therefor provided with legs of channel section, seat supporting arms of channel section pivoted to the legs and adapted to fit thereover when in folded position, a hollow post, means for pivoting the legs therein, locking rods connected to the legs and to said post, a bolt mounted in said hollow post, and a locking plate carried by said bolt, said locking plate being provided with grooves arranged to fit over the seat supporting arms when the chair is in position for use.

3. A collapsible chair or the like having a detachable seat portion and a supporting member therefor provided with legs of channel section, seat supporting arms of channel section pivoted to the legs and adapted to fit thereover when in folded position, a hollow post, means for pivoting the legs therein, locking rods connected to the legs and to said post, a bolt mounted in said hollow post, a locking plate carried by said bolt and adapted to engage the seat supporting arms when the chair is in position for use, and spring-pressed means for holding the locking plate in engagement with the supporting arms.

4. A collapsible chair or the like having a detachable seat portion, lugs carried thereby, and a supporting member therefor provided with legs of channel section, seat supporting arms of channel section pivoted to the legs and adapted to fit thereover when in folded position, a hollow post having a perforated frame thereon, pins on which the supporting arms and legs are pivoted passing through the perforations in said frame, locking rods connected to the legs and to said post, the free ends of the supporting arms being slotted for reception of the lugs carried by the detachable seat portion.

5. A collapsible chair or the like having a supporting member formed of foldable legs and supporting arms pivoted together

130

and adapted to fit over each other when in folded position, the free ends of the supporting arms being provided with slots, a seat and back portion of flexible material 5 hinged together and provided with strengthening rods adjacent their opposite edges, and locking lugs carried by the strengthen-

ing rods of the seat portion and adapted to enter the slots in said supporting arms.

ADDIS E. ALBERTIE.
